UNITED STATES PATENT OFFICE

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN

INTERNAL COMBUSTION ENGINE

Application filed December 30, 1929. Serial No. 417,361.

This invention relates to internal combustion engines and more particularly to the fuel feeding and exhaust systems of such engines.

5 It is one of the objects of the invention to provide an engine having an improved system of intake and exhaust passages and manifolds adapted to supply fuel mixture to and remove exhaust gases from the engine with 10 a minimum of frictional loss, so as to increase the volumetric efficiency, and to provide a cylinder block adapted to cooperate in the attainment of these results.

Another object of the invention is to provide 15 novel and effective means for heating the fuel mixture of such an engine with heat derived from the exhaust gases thereof, and to dispose of the gases so used in a clean and simple way.

20 A further object of the invention is to provide an engine having a cylinder block adapted for cooperation with said heating means.

Other objects of the invention will appear 25 from the following description taken in connection with the drawings, which form a part of this specification, and in which:

Fig. 1 is a view, partially in end elevation and partially in transverse vertical section, through an internal combustion engine 30 constructed in accordance with this invention;

Fig. 2 is a view partially in plan and partially in section substantially on the lines 35 2-2 of Figs. 1 and 3, and

Fig. 3 is a detail section taken substantially on the line 3-3 of Fig. 2.

Referring to the drawings, at 10 is shown 40 an internal combustion engine having a crank case 11 on which is mounted a cylinder block 12 provided with cylinders 13. This engine includes certain conventional elements, such as the cylinder head 14 adapted to close the cylinders 13 at their upper ends 45 and having a recess for each cylinder defining a combustion space 15 therefor, an oil pan 16 which closes the lower end of the crank case and forms a reservoir for lubricating oil for the engine, the crank shaft 17, 50 rotatably mounted in suitable bearings in

the crank case and having cranks by which it is driven through connecting rods 18 from pistons 19, one of which is mounted in each of the cylinders 13, and suitable ignition apparatus including a timing and distributing 55 device 21 through which electric current is provided for spark plugs 22, one of which is mounted in each of the combustion chambers.

The cylinder block 12 is provided with valve ports 23, which are preferably arranged in a row or line parallel to and adjacent the row of cylinders 13, and these ports communicate with the combustion spaces 15, there being two of the ports 23 for each of the cylinders. These ports are controlled 60 by suitable valves 24, illustrated as poppet valves of a conventional form, which seat on the periphery of the corresponding ports 23, and they are urged toward closed position by springs 25. The valves 24 are 65 opened against the springs 25 in proper sequence and in timed relation to the engine by mechanism including tappets 26, rocker arms 27 and cams 28, the cams being formed on a cam shaft 29 which is driven from the crank shaft 17 in any suitable manner, not shown. It will be understood that of the pair of ports 23 communicating with the combustion space of each cylinder, one operates to admit fuel mixture to the cylinder, 70 and the other to discharge the products of combustion therefrom, these ports being accordingly referred to as intake and exhaust 75 ports respectively.

To conduct the fuel mixture and the exhaust 80 gases to and from their respective ports 23, the cylinder block is formed with intake passages 31 and exhaust passages 32. These passages extend from their respective valve ports 23 through the cylinder block to the side thereof, terminating in intake ports 33 and exhaust ports 34 respectively, which are preferably inclined, or disposed diagonally to the horizontal. For this purpose the side 85 of the cylinder block is formed with an integral rib 35, longitudinally disposed, which provides a pair of adjacent inclined surfaces or planes 36 and 37, and the ports 33 and 34 are located in these faces. The face 36 in which the intake ports 33 are provided, is in 90 95 100

clined downwardly with respect to the horizontal, or with respect to a plane normal to the cylinder axes, and the face 37 in which the exhaust ports 34 are formed, is inclined in the opposite direction or upwardly.

Thus it will be seen that the intake passages 31 extend diagonally upwardly in a nearly straight line from the intake port 33 to the valve port 23. These passages are also 10 branched or widened out longitudinally of the engine to communicate with the intake valve ports 23 of two adjacent cylinders, as clearly shown in Fig. 2. Each of the intake ports 33, therefore, is connected to and adapted to serve two of the engine cylinders, the intake valves of adjacent cylinders being arranged in pairs for this purpose.

The exhaust passages 32 on the other hand, leave their exhaust valve ports 23 in a downward direction substantially parallel to the intake passages 31, but form an elbow curve upwardly to terminate at the upwardly disposed face 37 in the exhaust ports 34. In this way the intake and exhaust ports are disposed substantially at right angles to each other.

To supply fuel mixture to the intake ports 33, an intake manifold 38 is provided at the side of the engine and may be supported 30 from the inclined face 36. This manifold 38, best shown in Fig. 2, comprises a pair of conduits 39 and 41, having an integral central portion with a common wall 42. Disposed in either direction from the central portion of each of these conduits is a curved branch portion 43, extending inwardly toward the cylinder block, and having an upcurved end provided with a flange 44 by which it may be suitably attached to the face 36. The ends of the manifold branches are thus normal to the face 36 and in line with the passages 31, and each has its terminus in registry with the corresponding intake port 33.

The manifold conduits 39 and 41 are disposed in the same horizontal planes, the conduit 39 lying between the conduit 41 and the cylinder block. In this way the manifold is arranged so that each of its branches feeds only two of the engine cylinders. The inner conduit has its ends connected to the intake ports at the middle of the cylinder block and each of its branches feeds fuel to two of the four middle cylinders. The outer conduit 55 41 is connected at its ends to the intake ports at the extreme ends of the block, so that each branch of this conduit feeds the two cylinders at one end of the engine. This arrangement greatly improves the distribution of the 60 fuel mixture among the cylinders, and the engine efficiency, accordingly.

This also permits the branch portions of the manifold conduits to be constructed of considerable radius, making a smooth easy curve which may be followed by the fuel mix-

ture with a minimum of friction, thus greatly increasing the efficiency of the manifold.

The manifold conduits 39 and 41 are provided at the bottom of their central portions with ports 46 to which are connected the delivery pipes 47 of any suitable carburetor 48, which may be of the duplex type, having double carbureting elements arranged in parallel and supplied with liquid fuel from a single reservoir or float chamber. As carburetors of this nature are well-known in the art to which this invention relates, these parts are not shown in detail and it is unnecessary to describe them further. However, while the duplex carburetor as shown is preferred, it is to be understood that separate carburetors may be used to feed the manifolds independently.

To remove the exhaust gases, the ports 34 communicate with the branches 51 of an exhaust manifold 52 arranged, in the embodiment shown, above the intake manifold 38. These branches 51 are provided with terminal flanges 53 adapted to be clamped or otherwise secured to the upwardly disposed face 37 on the cylinder block. The upper surface of the manifold 52 is preferably provided with cooling ribs or flanges 54, and the manifold is connected at its end to an exhaust pipe (not shown) by which the exhaust gases are conducted away from the engine in the usual way.

The invention also provides novel and efficient means whereby the fuel mixture is heated by heat derived from the exhaust gases. To this end a portion of the intake manifold 38 is provided with a housing 55, surrounding and spaced from the outer wall of the conduits 39 and 41 to define a heating chamber or jacket 56.

Preferably the jacket 56 surrounds and is adapted to heat that portion of the manifold into which the carburetor tubes 47 discharge, and for this purpose is supplied with exhaust gases from the engine. The housing is provided with short conduits 57, at the ends of which are ports 58 which register with ports 59 in the lower inclined face 36 on the cylinder block. These ports 59 are respectively connected through branch passages 61 with the main exhaust passage 32 from two of the cylinders 13, the passage 61 forming a Y with the passage 32 in each case. In this way there is a direct connection between the exhaust valve port 23 of two of the cylinders and the jacket 56, so that part of the exhaust gases from these cylinders may pass directly into the jacket, the remainder going through the passages 32 and 51 into the exhaust manifold 52. It will be understood, however, that in the operation of the device, exhaust gases do not pass through the two passages 61 at the same time, since the two cylinders with which these passages communicate do not fire together. In the pre-

ferred embodiment, the passages 61 are connected to the exhaust passages from the two middle cylinders of the engine. When one of these cylinders is exhausting, part of its exhaust flows through the passage 61 and conduit 57 into one end of the jacket. In the meantime, the passage 61 to the other cylinder serves as an exhaust passage for the jacket, conducting the gases in a reverse direction, so that such gases as are in the jacket tend to escape through the Y connection via passage 51 into the exhaust manifold 52. Hence, the jacket 56 may be said to have two openings which act alternately both as inlets and as outlets for the jacket. While much of the gas entering the jacket is passed directly across to the other passage 57, still the effect is to keep the jacket more or less filled with fresh hot exhaust gas, which has a quasi circulation, passing around the jacket first in one direction and then in the other. This results in very effectively heating the intake manifold without the necessity either of providing a separate exhaust conduit for the jacket, or permitting the jacket gases to exhaust into the air.

The operation of this structure will be apparent from the above description, and its advantages will also be readily understood. By reason of the disposition of the intake manifold and the diagonally disposed intake ports, the number of turns in the path of the fuel mixture is a minimum thus greatly reducing the friction losses through the conduits and securing a larger volume of charge for a given vacuum. This, of course, increases the volumetric efficiency of the engine.

At the same time the invention provides a simple construction of manifolds which is easily manufactured and readily assembled, and in which the exhaust manifold and the intake manifold are entirely separate and independent of each other.

The disposition of passages in the cylinder block also permits the intake manifold to be heated by exhaust gases drawn directly from the engine exhaust ports, and the system of supplying these gases to the exhaust jacket secures effective heating without troublesome provision for removing the heating gases from the jacket.

While a specific embodiment of the invention has been herein described, which is deemed to be new and advantageous and may be specifically claimed, it is not to be understood that the invention is limited to the exact details of the construction, as it will be apparent that changes may be made therein without departing from the spirit or scope of the invention.

Having thus described the invention, what is claimed and desired to be secured by Letters Patent is:

1. The combination in an internal combustion engine of a cylinder block having valve

ports communicating with the cylinders, said block being formed on one side with adjacent faces diagonally disposed and provided with ports, passages in said block connecting the ports to said valve ports, and a manifold connected to the ports in each face. 70

2. The combination in an internal combustion engine of a cylinder block having exhaust and intake passages communicating with the cylinders, said passages terminating at the side of the block in planes substantially at right angles to each other. 75

3. The combination in an internal combustion engine of a cylinder block having exhaust and intake passages communicating with the cylinders, a longitudinally disposed rib on said block having faces disposed at right angles, and ports in said faces forming terminals for said passages. 80

4. The combination in an internal combustion engine of a cylinder block having longitudinally disposed faces inclined in opposite directions to a horizontal plane, exhaust ports in one of said faces communicating with the cylinders, intake ports in the other face communicating with the cylinders, and exhaust and intake manifolds connected to said exhaust and intake ports respectively. 85

5. The combination in an internal combustion engine of a cylinder block having adjacent faces on the side thereof inclined in opposite directions to a horizontal plane, exhaust ports in one of said faces communicating with the cylinders, intake ports in the other face each communicating with an adjacent pair of cylinders, and exhaust and intake manifolds connected to said exhaust and intake ports respectively. 95

6. The combination in an internal combustion engine of a cylinder block having cylinders arranged in line and valve ports for the cylinders arranged in line beside the line of cylinders, projections on the side of the block adjacent said valve ports defining faces inclined upwardly and downwardly respectively, ports in said faces, passages connecting the upwardly disposed ports to the exhaust valve ports, and passages connecting each downwardly disposed port to the intake valve ports of the adjacent pair of cylinders. 105

7. The combination with an internal combustion engine including a cylinder block having intake ports, of a manifold comprising conduits having contiguous middle portions and branches extending away from said middle portions and curved to terminate at said intake ports, the curve in each branch being of considerable radius and having an upward sweep at its terminal. 115

8. The combination with an internal combustion engine having exhaust and intake manifolds and exhaust passages communicating with said exhaust manifold, of a jacket 120

surrounding a portion of the intake manifold and branch passages connecting two of said exhaust passages to said jacket, said branch passages extending downwardly from and substantially at right angles to the exhaust passages.

9. The combination with an internal combustion engine having exhaust and intake manifolds and exhaust passages communicating with said exhaust manifold, of a jacket surrounding a portion of the intake manifold and having separated openings, and passages branched from two of the exhaust passages connected respectively to said openings, said branch passages extending downwardly from and substantially at right angles to the exhaust passages.

10. The combination with an internal combustion engine having exhaust and intake manifolds, of a cylinder block having diagonally disposed faces inclined toward said manifolds, exhaust passages in said block terminating in ports in one face connected to the exhaust manifold, intake passages in said block terminating in ports in the other face and connected to the intake manifold, a heating jacket for the intake manifold, and branch passages in the block connected to two of the exhaust passages and terminating in the face disposed toward the intake manifold connected to said jacket.

11. In an internal combustion engine, intake and exhaust manifolds, a heater jacket for the intake manifold, a cylinder block having diagonally disposed faces inclined towards the exhaust manifold and the heater jacket, exhaust passages in the block terminating in ports in the face inclined toward the exhaust manifold, branch passages connecting said ports to the exhaust manifold, auxiliary exhaust passages in the block terminating in ports in the face inclined toward the heater jacket, and branch passages connecting the last named ports to the heater jacket.

45 12. In an internal combustion engine, intake and exhaust manifolds, a heater jacket for the intake manifold, a cylinder block having diagonally disposed faces, one being inclined toward the exhaust manifold and the other toward the intake manifold and the heater jacket, exhaust passages in the block terminating in ports in the face inclined towards the exhaust manifold, branch passages connecting said ports to the exhaust manifold, intake passages in the block terminating in ports in the other face, branch passages connecting the last named ports to the intake manifold, auxiliary exhaust passages in the block also terminating in ports in the said other face, and branch passages connecting the last named ports to the heater jacket.

65 13. In an internal combustion engine, a cylinder block having intake and exhaust ports for each of the cylinders, intake and

exhaust manifolds arranged substantially in the same vertical plane, upwardly curving conduits connecting the intake manifold with the intake ports, and exhaust conduits curving downwardly from the exhaust ports and then upwardly substantially at right angles to connect with the exhaust manifold.

70 14. The combination in an internal combustion engine of a cylinder block having exhaust and intake passages communicating with the cylinders, said exhaust passages being curved to terminate in a diagonally upward direction and said intake passages being substantially straight to terminate in a diagonally downward direction, faces on one side of the cylinder block having ports in which the exhaust and intake passages terminate respectively, and exhaust and intake manifolds connected respectively to said ports.

75 15. The combination with an internal combustion engine having a cylinder block with cylinders disposed in line, said block having adjacent faces longitudinally disposed on the side thereof and inclined thereto above and below a horizontal plane, exhaust ports in the upwardly disposed face connected to each of the cylinders, intake ports in the downwardly disposed face each connected to adjacent cylinders, and a separate manifold for the ports above and below said plane.

80 16. In an internal combustion engine, the combination of a cylinder block having the cylinders arranged vertically and in line, a detachable cylinder head for the upper end of said block, said block having exhaust and intake passages communicating with the cylinders, said passages terminating at one side of the block and wholly below said head, the exhaust and intake passages terminating adjacent each other but in planes substantially at right angles to each other, and manifolds connected to said exhaust and intake passages.

85 In testimony whereof I affix signature.
JESSE G. VINCENT.
